UNITED STATES PATENT OFFICE.

JOHN C. RINGE, OF BRIDGEPORT, CONNECTICUT, ASSIGNOR TO THE SINGER MANUFACTURING COMPANY, A CORPORATION OF NEW JERSEY.

OVEREDGE SEWING-MACHINE.

1,156,820.

Specification of Letters Patent. Patented Oct. 12, 1915.

Application filed June 6, 1914. Serial No. 843,334.

To all whom it may concern:

Be it known that I, JOHN C. RINGE, a citizen of the United States, residing at Bridgeport, in the county of Fairfield and 5 State of Connecticut, have invented certain new and useful Improvements in Overedge Sewing-Machines, of which the following is a specification, reference being had therein to the accompanying drawings.

10 This invention relates to improvements in overedge sewing machines and has for its object to provide a lock-stitch sewing machine with improved means for carrying the needle-thread over the free edge of the fabric being acted on and concatenated with the lower or bobbin-thread at the under side of 15 the fabric.

In the accompanying drawings, which form a part of the specification, Figure 1 is a 20 front side elevation of a sewing machine fitted with the present invention; Fig. 2 an under side view of Fig. 1; Fig. 3 a perspective of the improved mechanism detached from the sewing machine. Fig. 4 diagrammatic views illustrating the action of the 25 thread-carrying looper at different stages in the formation of a given stitch. Fig. 5 is an enlarged view of the free end of the thread-carrying looper; Fig. 6 a view illustrating a portion of a seam as effected by 30 the present construction; Fig. 7 a plan of the loop-taker showing its loop-seizing point entering the needle-thread loop.

The present invention is shown as applied 35 to a Singer machine employing a loop-taker operated in a horizontal plane, but as it relates only to the construction and application of the thread-carrying looper, only such reference will be made to the other elements 40 of the machine as is deemed necessary for a proper understanding of its application.

Referring to the figures, 1 represents the 45 bed-plate upon which is mounted the bracket-arm comprising the arm standard 2 and arm bracket 3, 4 the main or needle-bar driving shaft carrying at its rear end the hand or band-wheel 5 and at its opposite end the usual take-up cam 6 for actuating the take-up lever 7, the front face of said 50 cam being provided with a stud-bearing (not shown) upon which is pivoted one end of a needle-bar actuating link 8 connecting the needle-bar 9 with the main-shaft 4.

10 denotes a spring depressed cloth-presser 55 carrying bar provided at its lower end with

a cloth-presser 11, and 26 the throat or needle-plate.

12 represents a rotary crank-shaft mounted in suitable bearings depending from the bed-plate and operatively connected with the main-shaft 4 through suitable quartering cranks, as 13, and crank connections, as 14, said crank-shaft being provided with a gear 15 which meshes with a gear 16 carried by the loop-taker actuating shaft 17, the ratio 60 of said gears being as two to one, thus giving to the latter shaft two rotations to one of the shaft 12.

18 represents the loop-taker provided with a suitable thread holding case 18' and carried by the loop-taker shaft 19 to the lower end of which is suitably secured a beveled gear 20 which meshes with a like gear 21 carried by the loop-taker actuating shaft 17, thus giving to said loop-taker two rotations 75 to one of the main-shaft 4.

22 denotes the arm bracket face-plate of usual construction and provided with a commonly employed thread-check 23, thread-tension 24 and thread-controller 25.

The means employed for giving to the fabric its feed movements and for controlling the amplitude of said movements may be of any approved construction, one form of which is partly shown in the drawings, 80 but it is not deemed necessary to specifically describe such mechanism since it is well understood.

Referring now to the parts more directly connected with the invention, 27 represents 90 a shaft bracket secured by screws, as 28, and depending from the under side of the bed-plate, 29 a rock-shaft mounted to oscillate in suitable bearings formed in said bracket and carrying a crank-arm 30 provided with a follower 31 tracking a heart-cam groove 32, formed in the face-cam 33 carried by the crank-shaft 12, the rock-shaft 29 carrying a bracket-collar 34 provided with a guide-pin 35.

36 represents an eccentric cam carried by the loop-taker actuating shaft 17 and provided with an eccentric strap connection 37, the outer end of which is connected by a ball-and-socket joint 38 with an arm 39 of 105 a bell-crank lever 40 pivoted on a stud-screw 41 threaded into the hub 42 of the shaft-bracket 27, the arm 43 of said bell-crank lever being forked to embrace a collar 44 loose on the shaft 29 and operatively con- 110

nected with said collar by pintle screws, as 45.

46 represents a looper carrying bracket whose lugs 47 and 48 are provided with suitable openings to receive the rock-shaft 29 and arranged at opposite sides of the collar 44, said looper carrying bracket having a suitable opening 49 to receive the pin 35 and in a suitable opening 50 is secured, by 10 screw 51, the thread-carrying looper 52 provided with a thread-engaging finger 53 and thread-engaging groove 54.

Having set forth the details of the invention, the following mode of operation and 15 coöperation of the several parts will be readily understood: Referring now to the thread-looper 52 and its actuating mechanism as when occupying the positions illustrated in Figs. 1, 2 and 3, and in side elevation and 20 plan views *a* and *b* respectively, of Fig. 4, with the needle 55 at nearly its limit of upward stroke as shown in said figures and views, the initial action of the heart cam-groove 32 on the crank-arm 30 acts to rock 25 the free end of the looper 52 toward the needle and simultaneously with said rocking movement the eccentric cam 36, through the connections previously pointed out, moves the finger 53 laterally across the line 30 of needle actuation and in contact with the needle-thread 56, as shown in side elevation and plan views *c* and *d* respectively, of Fig. 4. During the time that the cam-follower 31 is tracking the cam-groove 32 from 35 the point illustrated, best shown in Fig. 3, to substantially the point 57, the eccentric cam acts to give to the looper its reverse lateral movement to position the free end of the looper as shown in views *e* and *f*, of Fig. 40 4, thus carrying the needle-thread over the edge of the fabric, see Fig. 6, and into the groove 54, as shown in Fig. 5 and in views *e* and *f*, with the needle entering the needle-thread looper loop 58, when the tracking of 45 the cam-groove by its follower from the point 57 to the point 59, or point of reverse action of said cam-groove, the free end of the looper is rocked away from the line of needle actuation so that in its return movement from below the thread-plate the heel-portion 60 of the looper will pass clear of the needle, as illustrated in side elevation and plan views *g* and *h* respectively, of Fig. 4. During the time that the follower is 50 returning to its illustrated position the looper is rocked to its limit of upward movement, the eccentric cam in the meantime acting to return the looper to its illustrated position, best shown in views *a* and *b*. It being understood that the needle effects the usual thread-loop which is entered by the receiving point 61 of the loop-taker 18, see Fig. 7, and in the further rotation of the loop-taker cast the needle-thread about the bobbin 62 of the under thread 63, thus con-

catenating the latter with the needle-thread substantially as is illustrated in Fig. 6.

Having thus set forth the nature of the invention, what I claim herein is:

1. In an overseaming sewing machine, the 70 combination with a stitch-forming and cloth-feeding mechanism including a throat-plate, a needle provided with an upper thread and a loop-taker provided with a mass of under thread, of a needle-thread looper actuated to deliver said upper thread in the form of a loop over the free edge of the fabric being acted on and present said loop beneath said fabric to be entered by said needle and concatenated with said under thread, said actuating means including a cam member having one complete actuation to a like actuation of the needle for giving to said looper rocking movements, and a cam-member having two complete 75 actuations to one of said needle to give to said looper oppositely directed lateral movements at the upper, and at the under side of said throat-plate.

2. In an overseaming sewing machine, the 90 combination with a stitch-forming and cloth-feeding mechanism including a throat-plate, a needle carrying an upper thread and a loop-taker provided with a mass of under thread, of a needle-thread looper actuated to deliver said upper thread in the form of a loop over the edge of the fabric and present said loop beneath said throat-plate to be entered by said needle and concatenated with said under thread, said actuating 95 means including a cam-member for giving to said looper substantially uniform rocking movements and a cam-member for giving to said looper accelerated and retarded lateral movements, in the formation of a given 100 stitch.

3. In an overseaming sewing machine, the combination with a stitch-forming and cloth-feeding mechanism including a rock-shaft, a bell-crank lever, a throat-plate, a 110 needle provided with an upper thread and a loop-taker provided with a mass of under thread, of a needle-thread looper actuated to deliver said upper thread in the form of a loop over the free edge of the fabric being acted on and present said loop beneath said fabric to be entered by said needle and concatenated with said under thread, said actuating means including a heart-shaped cam-member operatively connected with said looper through said rock-shaft, and an eccentric cam-member operatively connected with said looper through the bell-crank lever, said rock-shaft and bell-crank lever acting to transmit to said looper rocking and 120 lateral movements, respectively.

4. In an overseaming sewing machine, the combination with a stitch-forming and cloth-feeding mechanism including a rock-shaft provided with a looper carrying 130

bracket, a bell-crank lever, a throat-plate, a needle provided with an upper thread and a loop-taker provided with a mass of under thread, of a needle-thread looper actuated 5 to deliver said upper thread in the form of a loop over the free edge of the fabric being acted on and present said loop beneath said fabric to be entered by said needle and concatenated with said under thread, said actuating means including a heart-shaped cam-member operatively connected with said looper through said rock-shaft and looper carrying bracket, and an eccentric cam-

member operatively connected with said looper through the bell-crank lever, said 15 rock-shaft and bell-crank lever acting to transmit to said looper carrying bracket, rocking and lateral movements, respectively.

In testimony whereof, I have signed my name to this specification, in the presence 20 of two subscribing witnesses.

JOHN C. RINGE.
